UNITED STATES PATENT OFFICE.

HARRY GRANT FRANCIS, OF RUSHVILLE, INDIANA.

ROLLER SCRAPER BAR FOR GLUE-SPREADING MACHINES.

Application filed April 10, 1922. Serial No. 551,124.

To all whom it may concern:

Be it known that I, HARRY GRANT FRANCIS, a citizen of the United States of America, and resident of 820 North Harrison Street, Rushville, in the county of Rush and State of Indiana, have invented certain new and useful Improvements in Roller Scraper Bars for Glue-Spreading Machines; and I do hereby declare the following to be a full and exact description thereof, reference being had to the accompanying drawings, making a part of this specification.

My invention relates to roller scraper bars for glue spreading machines, and it has for its object the improvement in construction of such devices whereby they are simplified and rendered more efficient in action.

The novelty of my invention consists in the combination and sub-combination of the parts as will be hereinafter set forth and specifically pointed out in the claims.

In the drawings, Fig. #1 is an end elevation of a machine embodying the improvements.

Fig. #2 is a side elevation at one end of a machine showing how the scraper rolls are driven. A is one end of a frame, B, the lower glue roll, B², is the upper glue roll, C is the lower scraper roll, and C², is the upper scraper roll. D is a worm gear that drives the lower scraper roll, D², is a worm gear that drives the upper scraper roll, B³, is the shaft of the upper roll B², B⁴ is the shaft of the lower roll B, C³, is the shaft of the upper scraper roll C², C⁴, is the shaft of the lower scraper roll C. Attached to the end of the shaft B⁴ is a gear E, which meshes with the gear E², it in turn meshes with gear E³, and gear E³ meshes with gear E⁴, which is attached to the end of the shaft B³ and drives the upper roll B². The upper scraper roll is operated by power being transmitted from the shaft B³, through bevel gears F, F², worm F³, worm gear D² which is attached to the end of the upper scraper roll shaft C³. The lower scraper roll is operated in a similar manner by power being transmitted from the shaft B⁴, through bevel gears G, G², worm G³, worm gear D, which is attached to the end of the lower scraper roll. Pivoted to the inner side of the ends of the upper trough M, are small plates M², that conform to the curve of glue roll B² and scraper roll C². This plate is for the purpose of preventing the glue in the upper trough M from leaking

out at the ends. This plate M² being pivoted to the ends of the upper trough M, allows it to conform to the changes that occur when the scraper roll C² is adjusted in relation to the glue roll B². A pan L is placed beneath the lower roll B for feeding glue to the lower roll. The upper roll B² has a pan M placed above it for providing glue for the upper roll. The glue roll B revolves in the same surface direction as the scraper roll C, also the glue roll B² revolves in the same surface direction as the scraper roll C². The surface speed of the scraper rolls C, C² is much less than that of the glue rolls B, B². The operation of my device is as follows: Power is applied to the opposite end of the lower glue roll B, to that which is shown, through gears E, E², E³, & E⁴ the power is transmitted to the upper roll B². In trying to overcome the objectionable features in the use of a continuously revolving scraper roll, it was found that by revolving the scraper roll in the same surface direction as its glue roll, less friction, and a closer adjustment and more even distribution of glue resulted.

The surface speed of the scraper roll should be much less than that of the glue roll. The operation of my scraper roll is as follows. Glue is placed in the upper and lower troughs M and L. The scraper rolls are placed in the right relation to the glue rolls, power is applied to the machine, causing the glue rolls and scraper rolls to revolve. The glue rolls being in contact with the glue in the troughs owing to the direction in which they revolve tend to carry the glue that adheres to the surface of rolls out of the troughs. The scraper roll owing to the direction it revolves tends to carry the glue back into the troughs, thus the thickness of the glue deposited on the stock will be determined by the relation of the scraper roll to the glue roll.

Having now described this invention and explained the mode of its operation, what I claim is:

1. The combination of upper and lower rolls, troughs for applying glue to the upper and lower rolls, scraper rolls, for regulating the amount of glue which adheres to glue rolls, the scraper rolls being driven by bevel gears, worm and worm gears, a plate attached to the ends of upper trough between the glue roll and scraper roll, all substantially as described.

2. The combination of upper and lower rolls, troughs, for applying glue to the upper and lower rolls, scraper rolls for regulating the amount of glue which adheres to glue roll, the scraper rolls being driven by bevel gears, worm and worm gears, a plate attached to the inner side of the ends of upper trough between the glue roll and scraper roll and of such a form as to conform to the contour of the scraper roll and glue roll, all substantially as described.
- 5 3. The combination of upper and lower rolls, trough for applying glue to the up-

per and lower rolls, scraper rolls for regulating the amount of glue which adheres 15 to glue rolls, the scraper rolls being driven by bevel gears, worm and worm gears, a plate pivoted to the inner side of the ends of the upper trough between the glue roll and scraper roll and of such a form as to 20 conform to the contour of the scraper roll and glue roll, all substantially as described.

HARRY GRANT FRANCIS.
